US00D742092S

(12) **United States Design Patent**
Sekula et al.

(10) **Patent No.:** US D742,092 S
(45) **Date of Patent:** ** Nov. 3, 2015

(54) **BODY-HUGGING BELT**

- (71) Applicant: **Airpressure Bodyforming GmbH**,
Berchtesgaden (DE)
- (72) Inventors: **Oliver Sekula**, Berchtesgaden (DE);
Hubert Greinwalder, München (DE);
Gert Rechenmacher, Kapfenberg (AT)
- (73) Assignee: **Airpressure Bodyforming GmbH**,
Berchtesgaden (DE)

(**) Term: **14 Years**(21) Appl. No.: **29/462,240**(22) Filed: **Jul. 31, 2013**(30) **Foreign Application Priority Data**

- Jan. 31, 2013 (EM) 002176305-0007
